A. H. PAPE,
ANTI GLARE AND RAIN ATTACHMENT FOR AUTOMOBILES.
APPLICATION FILED OCT. 9, 1919.

Patented Jan. 18, 1921.

UNITED STATES PATENT OFFICE.

AUGUST H. PAPE, OF KENTFIELD, CALIFORNIA, ASSIGNOR OF ONE-HALF TO
WILLIAM B. LARKINS, OF SAN FRANCISCO, CALIFORNIA.

ANTIGLARE AND RAIN ATTACHMENT FOR AUTOMOBILES.

1,366,022.

Specification of Letters Patent. Patented Jan. 18, 1921.

Application filed October 9, 1919. Serial No. 329,575.

To all whom it may concern:

Be it known that I, AUGUST H. PAPE, a citizen of the United States, residing at Kentfield, in the county of Marin and State 5 of California, have invented new and useful Improvements in Antiglare and Rain Attachments for Automobiles, of which the following is a specification.

The object of the present invention is to 10 provide an attachment for the hood of an automobile, or other vehicle, which can be extended for use to protect the driver of the vehicle from the glare of the sunlight and also to protect him from rain in rainy 15 weather.

In the accompanying drawing, Figure 1 is a plan view of a portion of the frame of my attachment in its collapsed position; Fig. 2 is a side view of the same, showing it 20 also in dotted lines in its extended position; Fig. 3 is a sectional view of a clamping device; Fig. 4 is a perspective view of a portion of said device; Fig. 5 is a side view and Fig. 6 is a sectional view of a modification; Fig. 7 is a side view and Fig. 8 is a broken 25 plan view showing a further modification; Fig. 9 is a sectional view of a radius link; Fig. 10 is a sectional view of an arm.

Referring to the drawing, 1 indicates the 30 front bow of the hood 41 of an automobile. Clamped to said bow and to the top of the stanchion 2 of the wind shield is a clamp 3. 4 indicates a second bow of the hood of the automobile. Extending from said second 35 bow forwardly to said front bow are rods 6, the rod on one side only being here shown, secured to said bows by screws 7 screwed into said rod, the front end of the rod bending downwardly, as shown at 8, out of alignment 40 with the remainder of the rod, for a purpose which will hereinafter appear.

9 indicates the main frame of my improved attachment of a general rectangular form with rounded corners. It is formed of 45 channel iron, the channel being directed inwardly. From the lower side of said channel shaped frame depend ears 11, between which is a spacing block 12. Screwed through said spacing block is the threaded 50 straight portion 13 of a draw bar 14, of which the outer portion 15 is bent almost at right angles to the straight portion to form a handle for turning said draw bar. Said straight portion of the draw bar 14 passes 55 loosely through clamp members 16, 17, and

upon the extreme end of said straight portion 13 is screwed a nut 18. The clamps 16, 17 are formed in their lower portions each with an approximately semi-circular recess 20 to receive the article to be clamped. The 60 clamp member 16 is provided with pins 19 which enter sockets 21 in the clamp members 17 to keep the clamp members in register with each other when partially separated. Upon turning the handle 15, the straight 65 portion of the bar is screwed through the block 12 and the clamp members are drawn toward each other, thus clamping the clamp upon the object desired. In the present instance, the clamps are clamped upon either 70 the rear portion of the rods 6, as shown in the collapsed position of the attachment, or in the front downwardly bent portions 8 thereof, as shown in dotted lines in Fig. 2.

To the front side of the frame 9 are attached pivot eyes 22 to which are pivoted, as shown at 23, the forked upper end 25 of rods 24 contained in tubes 26, the lower ends of which are secured, as shown at 27, to short stems 28 having formed integral therewith, 80 outside said tube, circular plates 29, pivotally mounted upon brackets 31 fastened around the lower end of the stanchions 2, said tubes swinging downwardly and forwardly as the attachment is moved from its 85 collapsed to its extended position. The inner ends of the rods 24 and the stems 28 are connected by stretched coiled springs 32 so as to normally hold said rods within said tubes. 90

The ends of the tubes 26 next to the forked ends of the rods 24 are split, as shown at 33, and threaded, as shown at 34, and on said threaded ends of the tube are nuts 36. The extreme outer ends of the tubes are beveled 95 and the ends of the nuts are also internally beveled, so that when the nuts are screwed on the threaded portions of the tubes, the beveled portions of the nuts engage the beveled portions of the tubes, forcing them inwardly, and clamping the rods in the positions to which they have been moved.

As the frame 9 is drawn forwardly to its extended position, the clamps 16, 17, slide upon the rods 6 until they reach collars 37 105 screwed upon the threaded front ends of rods 6. It is to accommodate the downwardly sloping position of the frame 9 in its extended position, that the front parts of the bar 6 are sloped downwardly. In either 110

position the springs 32 draw down the front end of the frame and prevent it from vibrating.

In the form of the invention shown in Figs. 5 and 6, the rods 6' do not extend the whole distance back to the second bow 2 but are secured to the upper ends of curved supports 38, the lower ends of which are clamped by bolts 39 to the main bow 1, the supports 38 being formed to allow the hood 41 of the automobile to hang in its natural position.

In the form of the invention shown in Figs. 7 and 8, the front part of the shield frame 9 is supported in the same manner as in the form of the invention previously described, but the rear portion is supported by pivotally attached extensible members 42 which are also pivotally attached to the bow 1. These extensible members each comprise a tube 43 containing a stretched coiled spring 44, the ends of which are attached to stems 45, 46, of which one, 45, is pinned to the tube 42 and pivoted to the bow 1, and the other, 46, is extensible from the tube and is attached to the ears 11 depending from the frame 9.

The frame 9 is formed with front and rear pairs of plate-like extensions or flanges 47 formed with holes 48, which engage alternately pins 49 extending from the bow 1 near

its front corners. When the attachment is extended, the pins 49 engage holes in the rear flange and when it is collapsed, they engage holes in the front flanges. In either case, the springs 44 in conjunction with the pins 49 hold the attachment in place.

I claim:—

1. The combination with the top, windshield and windshield stanchions of an automobile, of a glare and rain shield, arms pivoted at their ends to the stanchions and to the forward end of the glare and rain shield and rods mounted upon the upper side of said top, being pivotally connected with the inner end of the glare and rain shield and arranged to extend in front of the top and windshield to support the glare shield in downwardly and forwardly extending position in front of the windshield. 40

2. The combination with the top, windshield and windshield stanchions of an automobile, of rods mounted upon the upper side of said top and extending forwardly in front of said windshield, the forward ends 55 of said rods being turned downwardly obliquely, a glare and rain shield slidably and pivotally connected adjacent its rear end with said rods, and arms pivoted at their ends to the forward end of the glare and rain shield and to said stanchions. 60

AUGUST H. PAPE.
